Primary Examiner — Paula Allen Greene*(74) Attorney, Agent, or Firm* — Raghunath S. Minisandram(57) **CLAIM**

The ornamental design for a headphone, as shown and described.

DESCRIPTION

FIG. 1 is a perspective view of a headphone showing my new design, the opposite perspective view is a mirror image; FIG. 2 is a left side elevational view thereof; FIG. 3 is a right side elevational view thereof; FIG. 4 is a front view thereof; FIG. 5 is a back view thereof; FIG. 6 is a top view thereof; and, FIG. 7 is a bottom view thereof. The broken lines depict portions of the headphone that form no part of the claimed design.
